CLAIM

The ornamental design for a bath chair, as shown and described.

DESCRIPTION

FIG. 1 is a front and top perspective view of a bath chair showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear and bottom perspective view thereof.

FIG. 9 is an enlarged view of the bath chair taken from the circle part in FIG. 1; and,

FIG. 10 is an enlarged view of the bath chair taken from the circle part in FIG. 8.

The broken lines in FIGS. 1 and 8 are to annotate the enlarged views of FIGS. 9 and 10 and form no part of the claimed design.

1 Claim, 10 Drawing Sheets
